UNITED STATES PATENT OFFICE

171,578

COMBINED CAN AND COVER THEREFOR OR SIMILAR ARTICLE

Milton Brucker, Los Angeles, Calif., assignor to
Zenith Plastics Company, Gardena, Calif., a
corporation of California

Application February 9, 1953, Serial No. 23,521

Term of patent 14 years

(Cl. D58—17)

To all whom it may concern:

Be it known that I, Milton Brucker, a citizen of the United States, residing at Los Angeles, in the county of Los Angeles, State of California, have invented a new, original, and ornamental Design for a Combined Can and Cover Therefor or Similar Article, of which the following is a specification, reference being had to the accompanying drawing, forming a part hereof.

Figure 1 is a top perspective view of a combined can and cover therefor, showing my new design.

Figure 2 is a top perspective view thereof, showing the cover portion removed from the can.

Figure 3 is a bottom perspective view thereof.

Figure 4 is a bottom perspective view thereof, showing the cover portion removed from the can.

Figure 5 is a vertical cross-sectional view thereof taken on a line 5—5 of Figure 1.

Figure 6 is a vertical cross-sectional view thereof taken on a plane at right angles to the line 5—5 of Figure 1.

I claim:

The ornamental design for a combined can and cover therefor or similar article, as shown.

MILTON BRUCKER.
